United States Patent Office

Des. 216,242
Patented Dec. 2, 1969

216,242

SIGN

Mary N. Schmidt, 5305 Raeford Road,
Fayetteville, N.C. 28304

Filed Feb. 6, 1969, Ser. No. 15,673

Term of patent 14 years

Int. Cl. D20—03

U.S. Cl. D96—12

Fig. 1

Fig. 2

Fig. 4

Fig. 3

FIGURE 1 is a front elevational view of a sign showing my new design, the rear is a mirror image of the front showing;

FIGURE 2 is an elevational view taken from one end thereof, the opposite end being the same as the end shown;

FIGURE 3 is a top plan view thereof; and

FIGURE 4 is a partial cross-sectional view taken on line 4—4 in FIGURE 1.

I claim:

The ornamental design for a sign, as shown and described,
